UNITED STATES PATENT OFFICE.

CHARLES H. PUTNAM AND BERTHA PUTNAM, OF CHICAGO, ILLINOIS.

HAIR CURLER.

Application filed September 29, 1923. Serial No. 665,521.

To all whom it may concern:

Be it known that we, CHARLES H. PUTNAM and BERTHA PUTNAM, both citizens of the United States, and residents of the city 5 of Chicago, in the county of Cook and State of Illinois, have invented certain new and useful Improvements in Hair Curlers; and we do hereby declare that the following is a full, clear, and exact description of the 10 same, reference being had to the accompanying drawings, and to the numerals of reference marked thereon, which form a part of this specification.

This invention relates to a hair curler, and 15 particularly to a device of such construction that it is peculiarly adapted for use in imparting waves to short or "bobbed" hair.

It is desirable that such a device be easily applied and that it may be retained in an 20 operative position with a minimum of discomfort to the wearer, at the same time effectively imparting the desired configuration to the hair.

An important object of this invention consists in the provision of an inexpensive light 25 weight hair curler which fulfills the above requirements.

Another important object of this invention resides in the provision of a device of 30 the class described embodying resilient means for retaining the hair in association with the curler and for retaining the curler in operative position.

Other and further important objects of 35 this invention will be apparent from the disclosures in the specification and the accompanying drawings.

The invention (in a preferred form) is illustrated in the drawings and hereinafter 40 more fully described.

On the drawings:

Figure 1 is a fragmentary side elevation illustrating a device embodying the present invention in operative position.

Figure 2 is a view similar to Figure 1 showing the device as it appears when not in use.

Figure 3 is a side elevation of the device taken at right angles to the view shown in 50 Figure 2.

Figure 4 is a section on the line 4—4 of Figure 2.

Figure 5 is an end elevation of the view shown in Figure 1.

Figure 6 is a slightly enlarged section on 55 the line 6—6 of Figure 3.

As shown on the drawings:

The device of this invention comprises interfitting members 1 and 2 which are pivoted together intermediate their ends by a 60 pin 3 extending therethrough. The member 1 is of tubular material, either drawn or formed, and the member 2 is of tubular section and is provided with integral lugs 4 65 extending over the outside of the member 1 and having apertures therein through which the pin 3 is engaged. The members 1 and 2 are provided with oppositely positioned beveled faces 5 at one end thereof so that when said faces are moved toward each 70 other by pressing the ends of the members between the fingers the other ends thereof will be separated to receive the hair to which a desired configuration is to be imparted. The interfitting members 1 and 2 75 are adapted to be normally held in association with each other by means of a spring 80 which is coiled around the pin 3 and which has its free ends engaging the insides of said members 1 and 2 at points adjacent the 80 beveled faces thereof. An aperture 7 is formed in the member 2 at substantially the position shown in Figures 2 and 3, and engaged in this aperture by looping is a continuous resilient member 8, such as an ordinary rubber band, said member adapted to be stretched outwardly and engage in registering notches 9 formed in the ends of the members 1 and 2 in planes at right 85 angles to the beveled faces 5.

In using the device, the members 1 and 2 are forced apart by compressing the ends thereof adjacent the beveled faces 5, and the hair to be curled is engaged between said members and wound therearound the desired number of times. After the hair has been properly wound, the members are allowed to be sprung together by the spring 6, and the hair is further secured in position by engaging the continuous resilient 100 member 8 thereover and in the registering notches 9 in the manner indicated in Figures 1 and 5.

It will be apparent from the foregoing 105 description that the hair curler of this invention may be economically manufactured from any suitable material, such as light weight metal, and it will be further apparent that

the provision of the continuous member 8 affords additional means for properly securing the hair in position and for retaining the curler in a desired operating position relative thereto.

By the looping arrangement provided, it is possible to conveniently and effectively secure the resilient member 8 to the curler, and by providing the beveled faces 5 the necessity for a special handle is obviated. This is, of course, desirable where it is necessary to use a large number of the curlers simultaneously, as is usual in curling or waving short or "bobbed" hair.

18 We are aware that numerous details of construction may be varied through a wide range without departing from the principles of this invention, and we therefore do not purpose limiting the patent granted otherwise than necessitated by the prior art.

20 We claim as our invention:

1. A hair curler, comprising interfitting members pivoted together intermediate their ends, oppositely positioned beveled faces on said members at one end thereof, registering notches formed in the other end of said members, spring means tending to hold the

members in association, and continuous resilient means secured by looping to one of said members at the end thereof adjacent 30 the beveled face thereon and adapted to be engaged in said notches.

2. A hair curler, comprising interfitting members pivoted together intermediate their ends, oppositely positioned beveled faces on 35 said members at one end thereof, registering notches formed in the other end of said members, spring means tending to hold the members in association, and continuous resilient means secured by looping to one of 40 said members at the end thereof adjacent the beveled face thereon and adapted to be engaged in said notches, said resilient means when so engaged diverging from its point of permanent attachment towards opposite 45 sides of said interfitting members.

In testimony whereof, we have hereunto subscribed our names in the presence of two subscribing witnesses.

CHARLES H. PUTNAM.
BERTHA PUTNAM.
